(57) **CLAIM**

The ornamental design for a chaise sofa as shown and described.

DESCRIPTION

FIG. 1 is a perspective view of a chaise sofa according to an embodiment of the design shown in a first position.

FIG. 2 is a front view of the chaise sofa of FIG. 1 shown in the first position.

FIG. 3 is a rear view of the chaise sofa of FIG. 1 shown in the first position.

FIG. 4 is a left side view of the chaise sofa of FIG. 1 shown in the first position.

FIG. 5 is a right side view of the chaise sofa of FIG. 1 shown in the first position.

FIG. 6 is a top view of the chaise sofa of FIG. 1 shown in the first position.

FIG. 7 is a perspective view of the chaise sofa of FIG. 1 shown in a second position.

FIG. 8 is a front view of the chaise sofa of FIG. 1 shown in the second position.

FIG. 9 is a rear view of the chaise sofa of FIG. 1 shown in the second position.

FIG. 10 is a left side view of the chaise sofa of FIG. 1 shown in the second position.

FIG. 11 is a right side view of the chaise sofa of FIG. 1 shown in the second position.

FIG. 12 is a top view of the chaise sofa of FIG. 1 shown in the second position.

FIG. 13 is a perspective view of a chaise sofa according to another embodiment of the design shown in a first position, the embodiment being a mirror image of the embodiment shown in FIG. 1.

FIG. 14 is a front view of the chaise sofa of FIG. 15 shown in the first position.

FIG. 15 is a rear view of the chaise sofa of FIG. 15 shown in the first position.

FIG. 16 is a left side view of the chaise sofa of FIG. 15 shown in the first position.

FIG. 17 is a right side view of the chaise sofa of FIG. 15 shown in the first position.

FIG. 18 is a top view of the chaise sofa of FIG. 15 shown in the first position.

(Continued)

FIG. 19 is a perspective view of the chaise sofa of FIG. 13 shown in a second position.
 FIG. 20 is a front view of the chaise sofa of FIG. 13 shown in the second position.
 FIG. 21 is a rear view of the chaise sofa of FIG. 13 shown in the second position.
 FIG. 22 is a left side view of the chaise sofa of FIG. 13 shown in the second position.
 FIG. 23 is a right side view of the chaise sofa of FIG. 13 shown in the second position; and,
 FIG. 24 is a top view of the chaise sofa of FIG. 13 shown in the second position.
 Portions of the chaise sofa shown in broken lines are for illustrative purposes only and form no part of the claimed design.
